UNITED STATES PATENT OFFICE.

HERMAN R. BLUMBERG, OF RUTHERFORD, NEW JERSEY.

SAFETY ATTACHMENT FOR PRESSES.

1,085,529.

Specification of Letters Patent.

Patented Jan. 27, 1914.

Application filed September 23, 1913. Serial No. 791,410.

To all whom it may concern:

Be it known that I, HERMAN R. BLUMBERG, a citizen of the United States, residing at Rutherford, in the county of Bergen and State of New Jersey, have invented new and useful Improvements in Safety Attachments for Presses, of which the following is a specification.

The invention relates to safety devices, 10 and more particularly to the class of safety attachments for presses, such as power blanking presses used for piercing, stamping, forming, bending, etc.

The primary object of the invention is 15 the provision of an attachment of this character wherein the power mechanism of the press is locked so that it will be impossible for the operator to become injured thereby, as the attachment has to be manipulated by 20 both hands of the operator for tripping the power mechanism.

Another object of the invention is the provision of a safety attachment for presses 25 wherein the liability of injury to the operator, which frequently happens by not removing the hands from the press before the power mechanism is set in action, is obviated, the safety attachment being manually controlled and is adapted to be actuated by 30 both hands of the operator before the power mechanism can become active.

A further object of the invention is the provision of an attachment of this character wherein the press is provided with a 35 lock to prevent the release of the trip rod, thus enabling the controlling of the press by the operator, thereby enabling the handling of the work to and from the press with safety.

40 A further object of the invention is the provision of a device of this character which is simple in construction, reliable and efficient in its operation, and inexpensive in manufacture.

45 With these and other objects in view, the invention consists in the construction, combination and arrangement of parts as will be hereinafter fully described, illustrated in the accompanying drawing, and pointed out 50 in the claims hereunto appended.

In the drawing: Figure 1 is a side elevation of a press, showing the safety attachment applied thereto. Fig. 2 is a top plan view of the safety attachment. Fig. 3 55 is a fragmentary view similar to Fig. 1 looking toward the opposite side of the machine.

Similar reference characters indicate corresponding parts throughout the several views in the drawing.

Referring to the drawing by numerals, 5 designates generally a stamping or other press, and 6 the trip rod which is controlled by the foot treadle of the press for setting the power mechanism in action or stopping the same.

The safety attachment comprises a substantially U-shaped bail 7, the side limbs of which extend on opposite sides of the press and are connected to studs 8 which are screwed into the sides of the press and form 70 pivots for the said bail. Arranged exteriorly of the bail 7 parallel with the side limbs thereof are latch arms 9, each being supported upon a pivot stud 10 passed through the limbs adjacent thereto of the 75 bail, the said stud 10 being formed with an aperture or hole 11 in which is received the trip rod 6 of the press, the said rod being secured in the stud 10 through the medium of binding screw 12 which is threaded in the 80 stud and engages the said rod. Mounted in the outer free ends of the latch arms 9 are handles 13, while formed at the inner pivoted ends of the said arms are downturned latch extensions 14 which are adapted to 85 ride over and engage lock pins 15 screwed into the sides of the press, the latch extensions 14 being beveled at 16 to permit the riding thereof on to the lock pins 15 as shown in Fig. 1 of the drawing.

90 Mounted in the side limbs of the bail 7 are guide pins 17 which project into guide slots 18 formed in the arms 9, and these pins limit the swinging movement of the latch arms 9 when moved for disengaging the 95 latch extensions 14 from the lock pins 15 on the press and also to limit the swinging movements of the arms 9 when the latch extensions 14 automatically engage and lock with the said pins 15 for preventing the 100 trip rods 6 from being operated by the foot treadle of the press.

105 Suitably connected to the side limbs of the bail 7 and to the latch extensions 14 of the arms 9 are coiled retractile springs 19 which serve to hold the latch extensions 14 in the path of the lock pins so that the said extensions will automatically engage therewith for the locking of the trip rods when the power mechanism has moved to the 110 fullest extent of its up-stroke.

It will be apparent that before the power

mechanism can become active it is necessary for the operator of the press to grip the handles 13 and apply a downward pressure on the arms 9 for disengaging the latch extensions 14 from the lock pins, and thereafter the foot treadle can be operated for setting in motion the power mechanism of the press, and in this manner injury to the operator is avoided.

10 From the foregoing it is thought that the construction and manner of operation of the device will be clearly understood, and therefore a more extended explanation has been omitted.

15 What is claimed is:

1. A safety device for machinery comprising a movable bail, latch arms pivotally connected with the bail and having latch extensions, locking pins stationarily mounted upon the piece of machinery and engaged by the latch extensions to prevent the movement of the bail for setting in motion the power mechanism of the machinery.

2. A safety device for machinery comprising a movable bail, latch arms pivotally connected with the bail and having latch extensions, locking pins stationarily mounted upon the piece of machinery and engaged by the latch extensions to prevent the movement of the bail for setting in motion the power mechanism of the machinery, and means connected with the bail and the latch extensions for holding the latter in the path of the locking pin.

3. A safety device for machinery comprising a movable bail, latch arms pivotally connected with the bail and having latch extensions, locking pins stationarily mounted upon the piece of machinery and engaged by the latch extensions to prevent the movement of the bail for setting in motion the power mechanism of the machinery, means connected with the bail and the latch extensions for holding the latter in the path of the locking pin, and means on the bail and engageable with the arms to limit the swinging movement thereof.

4. A safety device for machinery comprising a movable bail, latch arms pivotally connected with the bail and having latch extensions, locking pins stationarily mounted upon the piece of machinery and engaged by the latch extensions to prevent the movement of the bail for setting in motion the power mechanism of the machinery, means connected with the bail and the latch extensions for holding the latter in the path of the locking pin, means on the bail and engageable with the arms to limit the swinging movement thereof, and handles carried by the latch arms.

In testimony whereof I affix my signature in presence of two witnesses.

HERMAN R. BLUMBERG.
